UNITED STATES PATENT OFFICE.

GEORGES GILES, OF FRIBOURG, SWITZERLAND.

LIGHTNING-ARRESTER.

1,111,453.

Specification of Letters Patent. Patented Sept. 22, 1914.

Application filed July 10, 1913. Serial No. 778,263.

To all whom it may concern:

Be it known that I, GEORGES GILES, engineer, a citizen of the United States, residing at Fribourg, Canton of Fribourg, in the 5 Confederation of Switzerland, have invented certain new and useful Improvements in Lightning-Arresters, of which the following is a specification.

The present invention relates to an 10 proved safety device for the dissipation of excess voltage in electrical systems, and is an improvement upon the apparatus described in Patent No. 1,040,927, granted to me October 8, 1912.

15 The device of my present invention comprises an adjustable spark gap in series with a high resistance and with a series of electrodes between which spark gaps are provided, and a movable conductor forming a 20 common element for a plurality of condensers, the other elements of which are the said electrodes, one extreme electrode being electrically connected to the said resistance while the other extreme electrode is electri-

25 cally connected to the said conductor. In order to obtain adequate protection of an electric line by means of a device of this kind, it is necessary for the apparatus to permit of an easy dissipation or discharge 30 of the excess voltages, limiting the value which practically can be given to the resistance in series with the spark gaps, in order that the device may have sufficient capacity for the discharge of an excess voltage. The device may be compared to a valve 35 in a water pipe, the opening of the valve, under excessive pressure being similar to the way of discharge of an excessive voltage therethrough. On the other hand, during

40 the dissipation of an excess voltage, the device must absorb a quantity of energy equal to that supplied by the central station or the generators feeding the line on which the device is placed. In order that this device 45 may not be destroyed by the quantity of energy to be absorbed it must be operated only during short intervals. In electric lines in which it is usual to employ protective devices of this nature, variations of tension 50 may occur and be maintained during an appreciable time, for which variations the device must be inoperative. Ordinarily these variations of tension do not exceed twice the normal voltage of the line. Therefore a 55 sufficient protection will be obtained by means of an apparatus regulated to operate

on excess voltages, which exceed twice the normal voltage of the line and which will not be destroyed in case of excessively abnormal voltages, and such an apparatus may 60 be obtained by the employment of a device which becomes inoperative after working a certain time. As the small condensers which connect the electrodes of the non adjustable spark gaps with the common conductor have 65 in a known manner one of their armatures formed by this conductor itself and the other armatures by the electrodes themselves, the extinction of the sparks in the spark gaps after a determined working-time 70 of the apparatus is obtained, according to the present invention, by means of the movability of the common conductor relatively to the electrodes. This movability breaks the connection between the conductor and the 75 small condensers after the apparatus has worked a given length of time.

The accompanying drawing is a longitudinal section and elevation of the apparatus. 80

a^1 , a^2 are the electrodes between which the adjustable spark gap is provided. These electrodes are placed in an envelop b , which is made for instance of glass and is arranged on the upper portion of a tube c of 85 insulating material upon which the wire d which forms the resistance in series with the electrodes a^1 and a^2 , is wound.

f^1 , f^2 , f^3 designate the electrodes of the non adjustable spark gaps the first of which 90 is connected to the resistance formed by the wire d . These electrodes are insulated from each other and from their common support consisting of the tube g on which they are placed, by means of insulating rings h . 95 Within the tube g of insulating material, the conducting rod i is placed. To this rod the last electrode f^{15} is directly electrically connected, this rod forming a common armature of small condensers the other armatures 100 of which are formed by the electrodes themselves and by means of which the electrodes are connected to the common conductor which is formed by the rod i . The latter is movable within the tube g which projects through the tube c and carries at its upper end the electrode a^2 . The rod i fits frictionally within the tube g in such a manner that in use it will not fall therefrom, as is indicated in the drawing, or, as will be understood, the rod i may be suitably supported 105 at the end thereof which extends beyond the

fixed electrodes so that in the use of the apparatus, the rod *i* is stationary and the other parts of the device moved upwardly when the excess voltage is discharged therethrough. In the latter a hole *a*³ is provided, which connects the inside of the envelop *b* with the inside of the tube *g*.

The electrode *a*¹ being connected to the line to be protected and the rod *i* to earth, 10 the electrode *a*² is nearly at the same voltage as the earth when the voltage of the line is normal and the apparatus is not in use. In the case of an excessive voltage a spark is caused to pass between the electrodes *a*¹ and 15 *a*² and is followed in the well known manner by the formation of sparks between the electrodes *f* in order to discharge the excess voltage to earth. The spark between the electrodes *a*¹ and *a*² causes the heating of the 20 air inclosed in the envelop *b*, which air passing into the upper portion of the tube *g* causes the displacement of the rod *i* with regard to the electrodes *f*. These electrodes then ceasing to be elements of condensers, 25 which they form with the rod *i*, as the other and common element, a voltage which is much higher than the starting voltage is necessary for making or maintaining the sparks in the spark gaps, and this assures 30 the extinction of the sparks after a short period of operating. Instead of placing the electrodes of the non adjustable spark gaps on a tube within which the rod forming the common conductor is slidably arranged, 35 these electrodes may for instance be arranged within a conducting tube serving as conductor and common armature to the small condensers which connect the electrodes to the conductor.

40 I claim as my invention:

1. A device of the character described, comprising adjustable electrodes providing a variable spark gap, a series of fixed spaced ring electrodes providing a plurality of intermediate constant spark gaps, and a con- 45

ductor movable within said fixed electrodes, the extreme end one of which is electrically connected to the said conductor while all of the others are insulated therefrom.

2. A device of the character described, 50 comprising a pair of adjustable electrodes providing a variable spark gap, a series of fixed spaced ring electrodes providing a plurality of intermediate constant spark gaps, a resistance connecting one member 55 of the said pair of electrodes and the end ring electrode next adjacent the same, and a conductor movable concentrically within the said fixed electrodes, the opposite extreme end one of which is electrically connected to the conductor while all the others are insulated therefrom.

3. A device of the character described, 60 comprising a housing, a pair of electrodes, one of which is fixed and the other movable 65 in the said housing, providing a variable spark gap therein, a casing connected to the said housing, a series of fixed spaced ring electrodes providing a plurality of intermediate constant spark gaps, a resistance surrounding the said casing and connecting the electrode fixed in the housing and the nearest adjacent of the said ring electrodes, a tube extending through the said series of 70 fixed ring electrodes and through the said 75 casing, and a conductor within the said tube and electrically connected to the fixed ring electrode at the opposite end of the series thereof, while all of the other ring electrodes are insulated from the said conductor and 80 from each other, there being a passage through the electrode fixed in the housing so as to provide communication between the interior thereof and the said tube.

In testimony whereof I have affixed my 85 signature in presence of two witnesses.

GEORGES GILES.
